(57) **CLAIM**

The ornamental design for an inflatable pool float, as shown and described.

DESCRIPTION

FIG. 1 is a front-perspective view of an inflatable pool float showing the claimed design.

FIG. 2 is a back-perspective view of the inflatable pool float shown in FIG. 1.

FIG. 3 is a front-side view of the inflatable pool float shown in FIG. 1.

FIG. 4 is a back-side view of the inflatable pool float shown in FIG. 1.

FIG. 5 is a left-side view of the inflatable pool float shown in FIG. 1.

FIG. 6 is a right-side view of the inflatable pool float shown in FIG. 1.

FIG. 7 is a top view of the inflatable pool float shown in FIG. 1; and,

FIG. 8 is a bottom view of the inflatable pool float shown in FIG. 1.

The dashed lines in the figures show portions of the inflatable pool float that form no part of the claimed design.

1 Claim, 8 Drawing Sheets
